Primary Examiner — Mary Ann Calabrese*Assistant Examiner* — Mark David Wolfley(74) *Attorney, Agent, or Firm* — Tucker Ellis LLP(57) **CLAIM**

The ornamental design for a chair, as shown and described.

DESCRIPTION

FIG. 1 is a front, right, top perspective view of a chair showing my new design;

FIG. 2 is a rear, left, bottom perspective view thereof;

FIG. 3 is a front view thereof;

FIG. 4 is a rear view thereof;

FIG. 5 is a top view thereof;

FIG. 6 is a bottom view thereof;

FIG. 7 is a right side view thereof; and,

FIG. 8 is a left side view thereof.

The broken lines in the drawings illustrate portions of the chair that form no part of the claimed design.
